UNITED STATES PATENT OFFICE.

ROY WATT, OF HEALY, KANSAS.

CHUTE.

Application filed November 21, 1924. Serial No. 751,357.

To all whom it may concern:

Be it known that I, ROY WATT, a citizen of the United States, residing at Healy, in the county of Lane and State of Kansas, have invented new and useful Improvements in Chutes, of which the following is a specification.

This invention relates to a device for holding a cow to enable the cow to be dehorned, the general object of the invention being to provide means whereby the cow can be firmly held by its neck and head and the head moved into a position where the dehorning operation can be easily carried out.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a front view of the device.

Figure 2 is a side view.

Figure 3 is a top plan view.

Figure 4 is a detail sectional view.

Figure 5 is a section on line 5—5 of Figure 2.

In these views, 1 indicates a stall into which the cow to be dehorned is driven, the front of the stall being provided with a hinged lower door 2 and a vertically movable upper door 3. The door 3 is adapted to be actuated by means of a hand lever 4 pivoted at one end to a part of the stall and connected by a pin and slot connection 5 to the door. A counter weight 6 is connected with the lever by means of a cable 7 which passes over a pulley 8 on a part of the stall. The abutting ends of the two doors are provided with V-shaped recesses 9 which when the doors are closed forms a diamond-shaped opening for receiving the neck of the cow. A spring 10 is adapted to open the lower door 2 and this door is kept closed by means of a latch 11 which is adapted to be moved to releasing position by means of a pedal 12, the lever 13 and the rod 14 which is pivoted to the lever and which engages the latch so that when the pedal is depressed the rod is forced up-

wardly by the lever and thus moves the latch to releasing position. A trough 15 has one end pivoted to the lower door immediately under the recess therein, as shown at 15' so as to receive the cow's head and this trough can be adjusted from a horizontal position to an inclined position and vice versa by means of a hand lever 16 which is pivoted to a bracket 17 and which has its pawl 18 engaging a toothed sector 19 which is formed on a bracket 20, the brackets 17 and 20 being supported on the lower door. A brace 20' is provided for the bracket 20, the upper end of this brace being fastened to the door. Links 21 connect the lever with the trough. A pair of loops 22 is carried by the trough, one end of each loop being pivotally connected with one side of the trough and the other end being adjustably connected with the other side of the trough by means of a bracket 23 and a spring plunger 23' for engaging any one of a number of notches 24 in the loop. By forcing the notched end of the loop into the bracket a notch therein will be engaged by the plunger 23' to automatically lock the loop in closed position.

The upper door is first raised and then the animal driven into the stall until it places its head and neck over the lower door. The upper door is then lowered by means of the lever so as to seize the neck of the animal by the walls of the opening 9. The animal's head is then pressed down into the trough and the loops put in place, one over its neck and the other over its nose so that the animal's head is held in flattened condition in the trough. The trough is then lowered on its hinge so as to place the animal's head in the most favorable position where its horns can be operated upon by the dehorning tool. After the animal has been dehorned the upper door is raised and the latch 11 of the lower door raised by means of the pedal 12 and its connections so that the lower door will swing open and thus permit the animal to pass from the stall. Then the lower door is swung closed so that another animal can be operated upon.

It is thought from the foregoing description that the advantages and novel features of my invention will be readily apparent.

I desire it to be understood that I may make changes in the construction and in the combination and arrangement of the several

parts, provided that such changes fall within the scope of the appended claims.

What I claim is:—

1. An apparatus of the class described comprising a stall, a hinged lower door and a vertically movable upper door at one end thereof, the abutting ends of the doors having recesses therein for forming an opening to receive the neck of an animal when the doors are closed, a trough hinged to the lower door under the opening for receiving the head of the animal, means for adjusting the trough and means for holding the head of the animal in the trough.
- 15 2. An apparatus of the class described comprising a stall, a hinged lower door and a vertically movable upper door at one end thereof, the abutting ends of the doors having recesses therein for forming an opening to receive the neck of an animal when the doors are closed, a trough hinged to the lower door under the opening for receiving

the head of the animal, means for adjusting the trough, means for holding the head of the animal in the trough, such means comprising loops carried by the trough.

25 3. An apparatus of the class described comprising a stall, a hinged door and a vertically movable door closing one end thereof, the abutting ends of the doors having recesses therein for forming an opening to receive the neck of an animal when the door is closed, a hand lever for moving the upper door vertically, a latch for holding the lower door closed, a spring for opening the lower door, manually operated means for raising the latch, a trough hinged to the lower door under the opening, manually operated means for adjusting the trough, loops each having one end pivoted to the trough and means engaging the other ends of the loops for holding them in closed position.

30 35 In testimony whereof I affix my signature.

40 ROY WATT.
